DESIGN FOR A HEATING FURNACE

Allen J. Johnson, Primos, Pa.

Application January 20, 1934, Serial No. 50,511

Term of patent 14 years

To all whom it may concern:

Be it known that I, ALLEN J. JOHNSON, a citizen

of the United States, and a resident of Primos, county of Delaware,

and State of Pennsylvania, have invented a new, original, and ornamental

Design for a Heating Furnace, of which the fol-

lowing is a specification, reference being had to

the accompanying drawing, forming a part as shown.

Figure 1 is a plan view of a heating furnace;

Figure 2 is a view in front elevation of the same

heating furnace;

Figure 3 is a view in side elevation of the same

heating furnace.

I claim:

The ornamental design for a heating furnace,

the accompanying drawing, forming a part as shown.

ALLEN J. JOHNSON.
